DRIVE FOR A PENDULUM, SWING
OR THE LIKE

Joseph F. Punzak, Brooklyn, N. Y., assignor to
United Metal Goods Manufacturing Co., Inc.,
Brooklyn, N. Y., a corporation of New York

Application June 13, 1950, Serial No. 167,847

12 Claims. (Cl. 58—26)

1

This invention relates to electric clocks, and is particularly directed to operating mechanism for a pendulum, swing or the like.

Electric clocks have been provided with swings, pendulums and the like, operated from the same motor that drives the clock. However, this imposes a slight additional load on the clock, which in some cases may be undesirable as affecting the accuracy of the clock.

An important object of this invention is to provide actuating mechanism for a pendulum or swing, operated by a motor entirely separate from the motor that operates the clock hands.

However, the actuating mechanism for the pendulum or swing may, if desired, be operated by the same motor that operates the clock.

The operating unit or assembly forming the subject matter of this invention, and which, as noted, may be operated by its own motor, or by the clock motor, comprises a continuously rotating shaft, mounted in a hollow core. This shaft carries a cam which bears against the inner end of a piston-like member, which projects laterally through the core member. This piston bears against the mid portion of an inclined carrier plate, which is pivoted to the clock frame at its upper end; pivotally suspended from the lower end of this inclined carrier plate is a swing or pendulum, the weight of which causes the inclined plate to bear against the piston. The piston pushes the carrier plate outwardly and gravity causes the carrier plate to follow the piston on its return stroke, the reciprocation of the piston operating the swing or pendulum.

The carrier plate, as mentioned, may be inclined. However, the carrier plate may be positioned vertically. Where the carrier plate is inclined, the weight of the swing or pendulum tends to hold the swing against the piston; however, a light spring may be used, for pressing the carrier plate against the piston at all times, to avoid backlash. Where the carrier plate is vertical, the spring is necessary for holding the plate in contact with the piston.

The described operating unit may be positioned to operate the swing fore and aft, or laterally, as may be desired.

Fig. 1 is a front view, showing the improved drive of this invention, having a motor separate from the clock motor, fore and aft swing.

Fig. 2 is a side view of Fig. 1.

Fig. 3 is an enlarged section of the main portion of the drive.

Fig. 4 is a section on line 4—4 of Fig. 3.

Fig. 5 is a front view of a modification, having

2

a motor separate from the clock, lateral or side-wise swing.

Fig. 6 is a side view of Fig. 5.

Fig. 7 is a front view, and Fig. 8 an end view, where the clock motor also operates the swing, which moves fore and aft.

Figs. 9 and 10 are front and side views of a modification, where the carrier plate is vertical.

Figs. 11 and 12 are side views, showing the use of springs with inclined carrier plates.

Referring now to these drawings, 2 is a portion of a clock frame, the dial, clock frame, gearing and motor (not shown) being mounted in the space indicated generally at 4. A mounting plate 6 is secured in any convenient way to base plate 2. The plate 6 supports studs 8, into which screws 10 are threaded, these studs and screws supporting a base plate 12, having arms 14 for supporting a constant speed motor of known construction, the rotor of which is shown at 16.

The shaft of the motor drives a worm 18, Fig. 3, which drives a toothed fiber gear 20 fixed on shaft 22. Shaft 22 carries a toothed gear 24 driving a gear 26, fixed on shaft 28, journaled in bearings 30 in a hollow core member 32.

Core 32 is supported by a right angled flanged bracket 33, secured to plate 6, the bracket having an aperture to receive the reduced portion 32' of the core. Shaft 28 carries a plural faced cam 34, having as many contact points as desired, conveniently three.

Core 28 is provided with a piston-like member 36, having a rounded head 38 engageable by the cam 34. Piston 38 projects laterally for some distance beyond the outer surface of core 32, and engages the intermediate portion of an inclined carrier plate 40. Carrier plate 40 is pivotally mounted at its upper end by a pin 42, passing through ears 44 on the plate and mounted in posts 46 on plate 6.

The lower end of carrier plate 40 is provided with bent ears 48, through which passes a pivot pin 50, on which pin wires 52 are freely pivoted. Wires 52 are formed into a swing like and pendulum like member 54, on which a figurine 56 may be seated. The swing 54 hangs vertically and the pivot 42 is so located with respect to core 32 that the carrier plate 40 is at an incline to the vertical, whereby the weight of the swing, and of the carrier plate itself, causes the carrier plate to be pressed into constant contact with piston 36, pressing it into contact with the rotating cam 34.

In operation, the constantly rotating shaft 22 drives cam shaft 28, cam 34 as it rotates causing

the piston to move outwardly, pushing the carrier plate 40, causing the swing or pendulum 54 to oscillate fore and aft with respect to the clock in space 4. On the return or inward stroke, plate 40 follows the piston and then is pushed outwardly by the next stroke of the piston. The period of oscillation may be regulated by the length of the swing and by the ratio and number of teeth in the several reduction gears 18, 20, 24 and 26.

In the modification shown in Fig. 5, the swing is driven by its own motor 16 and is arranged to swing laterally, instead of fore and aft. The construction is similar to that of Fig. 1, the principal difference being that the core 32a is at right angles to the base plate 6, instead of parallel with it, as in Fig. 1.

In Fig. 5, any simple reduction gear driven from the motor shaft may be provided; for example, a worm 56 driven by the motor shaft drives a toothed gear 58 mounted on shaft 59, which is provided at its outer end with a worm 60, driving a toothed fiber gear 62 on shaft 64. Shaft 64 carries a worm 66 meshing with toothed gear 68, which drives shaft 28 of core member 32a, positioned at right angles to base plate 6. Shaft 28, as before, has a cam 34 operating a piston 36, in engagement with an inclined carrier plate 40a, pivoted at its upper end on pin 69 and carrying at its lower end a pivotally suspended swing or pendulum 70. As before, the weight of the swing keeps the carrier plate 40a pressed against piston 36, the reciprocation of which causes the swing 70 to swing laterally. As before, the period of oscillation may be varied by selecting the length of the swing 70, and by the control of the sizes of the driving gears.

In the description above, the actuation of the pendulum or swing is by a motor separate from the clock motor. However, a generally similar operating unit may be used, for actuation by the clock motor.

In this construction, referring to Figs. 7, 8 and 9, the clock motor 74 operates the shaft 76 for driving the usual train of gears for operating the hands of the clock. In order to actuate the swing, shaft 76 is provided with a worm 78 meshing with a toothed gear 79 on vertical shaft 80, journaled in brackets 82. The shaft 80 carries, at its lower end, a gear 24b (analogous to gear 24, Fig. 1), which meshes with gear 26b driving a shaft 28b journaled in core 32b. A three sided cam 34b operates a piston 36b, which in turn bears against and actuates carrier plate 40b carrying a swing 52b, which, like swing 52, swings fore and aft. Core 32b is shown as vertically positioned, but it could be horizontally positioned, if desired, by using a worm wheel and gear like 66 and 68, Fig. 5, at the lower end of shaft 80.

In order to operate the swing or pendulum laterally from the clock motor, the core 32b and carrier plate 40b would be positioned in a position 90° away, around a vertical axis, from the position shown in Fig. 8, and would be driven by shaft 80, in turn driven by the clock motor, as in Fig. 8. This would give a lateral push to the swing, so that it would swing laterally, instead of fore and aft.

In the modification shown in Fig. 9, the carrier plate 85 is provided with bent ears 86 provided with holes for receiving a pivot rod 87 supported by standards 88. This carrier plate 85 is provided with holes 89 for loosely receiving the bent ends 90 of wires 91 forming a pendulum or swing. The base plate 6 is provided with a stud 92 passing loosely through a hole in the base plate, the outer

end of the pin 92 being threaded to receive a nut 93. A washer 94 loosely surrounds the pin 92 and a compression spring 95 is confined between nut 93 and washer 94. Plate 85 is rocked on pivot 87 by a piston 36 carried by core 32 and reciprocated as already described. Spring 95 presses the plate 85 into contact at all times with the plate. The tension on the spring 95 may be adjusted by nut 93, an adjustment which varies the amplitude of the swing 91.

A similar type of spring may be used in connection with an inclined carrier plate, as shown in Figs. 11 and 12. In Fig. 11, a pin 96 carried by the base plate 6 passes loosely through a hole in the inclined carrier plate 40, and a compression spring 97 confined between nut 98 and a beveled washer 99 presses the carrier plate into contact with the piston 36.

In Fig. 12 a similar construction is illustrated, where the pin 100 is bent as shown so as to pass loosely through the carrier plate 40 at substantially right angles thereto. A compression spring 95 of the type shown in Fig. 10 presses the carrier plate into contact with the piston 36.

While the invention has been illustrated in some detail, it should be understood that the invention is not limited to precisely the details shown, but may be carried out in other details.

I claim as my invention:

1. A drive for a clock pendulum, swing or the like, comprising a rotatable shaft, a motor geared to said shaft for rotating it, a cam carried by said shaft, a reciprocable piston operated by said cam, a carrier plate in operative engagement with said piston for actuation thereby, and a pendulum pivotally suspended from said carrier plate, said carrier plate being positioned at an angle to the vertical, so that the weight of said swing tends to hold the carrier plate in engagement with said piston.

2. A drive for a clock pendulum, swing or the like, comprising a rotatable shaft, a motor geared to said shaft for rotating it, a cam carried by said shaft, a reciprocable piston operated by said cam, a carrier plate, pivotally mounted at its upper end with its intermediate portion in operative engagement with said piston, and a swing pendulum member suspended for free pivotal movement from the lower end of said carrier plate, said carrier plate being positioned at an angle to the vertical, so that the weight of said swing pendulum member tends to hold the carrier plate against said piston.

3. A drive for a clock pendulum, swing or the like comprising, a base plate, a core member mounted on said base plate, a shaft journaled in said core member, a motor geared to said shaft for rotating it, a cam carried by said shaft, a reciprocable piston carried by said core and in operative engagement with said cam, and projecting laterally from said core member, and a swing pendulum operatively converted with said piston for operation thereby.

4. A drive for a clock pendulum, swing or the like comprising, a base plate, a core member mounted on said base plate, a shaft journaled in said core member, a motor geared to said shaft for rotating it, a cam carried by said shaft, a reciprocable piston carried by said core and in operative engagement with said cam, and projecting laterally from said core member, a carrier plate in operative engagement with said piston, and a swing pendulum member freely pivoted at the end of said carrier plate.

5. A drive for a clock pendulum, swing or the

like, comprising a base plate, a core member mounted on said base plate, a shaft journaled in said core member, a motor geared to said shaft for rotating it, a cam carried by said shaft, a reciprocal piston, in operative engagement with said cam, and projecting laterally from said core member, a carrier plate, pivoted at its upper end and having its intermediate portion in operative engagement with said piston, and a swing pendulum freely pivoted at the lower end of said carrier plate, said carrier plate being positioned at an angle to the vertical, so that the weight of said swing pendulum member tends to hold the carrier plate in contact with said piston.

6. A drive for a pendulum, swing or the like, comprising a pivoted carrier plate, a reciprocable piston in operative engagement with said carrier plate, spring means for pressing said carrier plate toward said piston, and a pendulum member carried by said carrier plate.

7. A drive for a pendulum, swing or the like, comprising a vertically positioned carrier plate, pivotally mounted at its upper end, a swing member pivotally carried by the lower part of said carrier plate, reciprocable means, engageable with the intermediate portion of said plate, and spring means for pressing the carrier plate into engagement with said reciprocable means.

8. A drive for a pendulum, swing or the like, comprising a rotatable shaft, a motor geared to said shaft for rotating it, a cam carried by said shaft, a reciprocal piston operated by said cam, a carrier plate adapted to be actuated by said piston, spring means for pressing said carrier plate toward said piston, and a pendulum swing member pivoted freely to the lower part of said carrier plate.

9. A drive for a clock pendulum or the like, comprising a rotatable shaft, a motor geared to said shaft for rotating it, a carrier plate pivoted on a horizontal axis above said rotatable shaft, a pendulum swing pivoted to said carrier plate on a horizontal axis located at a level below said rotatable shaft, a cam carried by said rotatable shaft, and a piston positioned to reciprocate longitudinally in a substantially horizontal, rectilinear path, to be operated by said cam and to engage said carrier plate.

10. A drive for a clock pendulum or the like, comprising a rotatable shaft, a motor geared to said shaft for rotating it, a carrier plate pivoted on a horizontal axis above said rotatable shaft, a pendulum swing pivoted to said carrier plate on a horizontal axis, located at a level below said rotatable shaft, a cam carried by said rotatable shaft, a piston positioned to be operated by said cam and to engage said carrier plate, and a hollow core member in which said rotatable shaft is mounted, said core member being provided with a transverse passage in which said piston reciprocates.

11. A drive for a clock pendulum or the like, comprising a rotatable shaft, a motor geared to said shaft for rotating it, a carrier plate pivoted on a horizontal axis above said rotatable shaft, and positioned at an angle to the vertical, a pendulum swing pivoted to said carrier plate on a horizontal axis, located at a level below said rotatable shaft, a cam carried by said rotatable shaft, a piston positioned to be operated by said cam and to engage said carrier plate.

12. A drive for a clock pendulum or the like, comprising a rotatable shaft, a motor geared to said shaft for rotating it, a carrier plate pivoted on a horizontal axis above said rotatable shaft, a pendulum swing pivoted to said carrier plate on a horizontal axis, located at a level below said rotatable shaft, a cam carried by said rotatable shaft, a piston positioned to be operated by said cam and to engage said carrier plate, and a spring for pressing said carrier plate into engagement with said piston.
